UNITED STATES PATENT OFFICE.

GEORGE H. EARLE, OF VALPARAISO, INDIANA.

COMBINED HEATER AND MUFFLER.

Application filed February 1, 1921. Serial No. 441,704.

To all whom it may concern:

Be it known that I, GEORGE H. EARLE, a citizen of the United States, residing at Valparaiso, in the county of Porter and State of Indiana, have invented certain new and useful Improvements in Combined Heaters and Mufflers, of which the following is a specification.

My invention relates to a combined heater and muffler and it consists more especially of the features hereinafter pointed out in the annexed claims.

The purpose of my invention is to provide a unitary device which utilizes the maximum radiation from an automobile muffler to warm a cold stream of air from within the car and again return the same in a heated state; that provides means to control the volume of heated air; that employs the exhaust gases at their highest temperatures to serve as a heating agent; that thereafter gradually reduces the pressure of such gases to effectively muffle the same and accomplish this without filling the passageways with deposited carbon; and that in addition secures these results in a simple and economical manner without complex and intricate mechanism.

With these and other ends in view I illustrate in the accompanying drawing such instances of adaptation that will disclose the broad underlying features of my invention, without limiting myself to the specific details of construction shown thereon and described herein.

Fig. 1 is a side elevation of a complete device, in position.

Fig. 2 is an end elevation of Fig. 1, partly in section.

Fig. 3 is a side elevation of Fig. 2, in section, showing parts broken away.

Fig. 4 is a perspective view of the external casing partially broken away to show the interior structure.

Fig. 5 is a perspective view of one of the louvres, detached from the rest of the associated structure.

In carrying out the various features of my invention, I may use the details shown or any equivalents thereof as may be found desirable. The present exemplification comprises a heater that surrounds a specially constructed muffler and which delivers the heated air within the car as directly as possible. It, in the main, consists of a muffler 1 having an inlet 2 to receive the exhaust

gases of the engine (not shown) and an outlet 3. These are formed in heads 4 that abut the outer casing 7 and the tie rods 12 hold these parts assembled. Within the outer tube or casing 7 an intermediate tube 6 is placed and inside of this an inner tube 5 is secured. Between tubes 6 and 7 an outer passage 9 is formed and between tubes 5 and 6 an intermediate passage 10 is also formed. Openings 11 lead from the latter passage to the interior of tube 5. These passages encircle the tubes, and at the inlet end they are all closed by the conical deflector 8, except the outer passage. 70

In this invention the hottest gases are first delivered to the outer passage 9 so that the full benefit of their heat is secured for the heater which surrounds the major portion of the muffler's length. By reason of this envelopment of the muffler the gases within it are not cooled too quickly thus avoiding the accumulation of carbon. In mufflers of the ordinary type the hottest gases are first led into an inner tube to prevent their too sudden cooling, for the same reasons mentioned above. 80

With my improvement I gain this advantage by securing a complete cooperation between the heater and the muffler, making the muffler dependent on the heater and the heater on the muffler, by reason of my first leading the hottest gases near the warm air passages of the heater. 90

The heater casing may be made in any desired relation with respect to the way its sides and ends are secured to each other, whether made of separate pieces or otherwise. It has ends 13 in which openings 14 are formed to receive the muffler 1. The sides 16 are curved approximately as shown. They do not extend the full depth of the ends 13, but terminate in an inwardly projecting flange 17 and the ends 13 depend below this point at 15. 95

The upper edges 18 of the sides are straight to enter an opening made in the floor 20 of the car; also to coat with the floor grating 21. The ends 13 are also provided with holes 19 to receive pins 22 of the louvres or damper ends 27 on which the latter are pivoted for movement in opening or closing the air passages of the heater. 105

The louvres are clearly shown in Fig. 5. They are made in right and left pairs, that shown being the left hand one. The sides 23 are curved so as to be approximately 110

concentric with the muffler 1 when in an open position. The extreme bottom is formed as an apron 26 from which a narrow curved portion 25 extends upward to the edge of a lengthwise slot 24 that is made about the full length of the inside of the heater.

At the upper edge 28 the louvre is made straight from its junction with the side 23 upward. The portions 28, 23, 25 and 26 have inwardly projecting flanges 27 in which holes 29 are formed. These holes register with holes 19 of the outer casing. Pins 22 are placed in them, on which the louvres are pivoted; the flanges 27 in contour at the lower part at 30 are made on the same radius as the muffler 1 to fit snugly against it when the louvre is opened, and another contour 31 higher up of the same radius but eccentrically placed. This forms an abutment when the louvres are closed. When the louvres are open slots 32 formed in the ends 27 permit the flanges 17 of the outer casing to enter whenever the louvres are closed.

25 To operate the louvres, projections 33 are attached at one end. These are slideable in slots 36 formed at the same end of the grating 21, so as to control the flow of cold air from within the car down the two cold air passages, 34, past the flanges 17, through the openings 24 into contact with the heated outer tube of the muffler and upward through the warm air passages 35 into the interior of the car.

30 It is no limitation to make the heater shorter than the length of the muffler, as instanced in the drawing, for this relation may be varied as needed without departing from the spirit of my invention.

35 What I claim is:

1. In heaters, a suitable casing, a muffling element within the casing, a heat radiating surface exterior of the muffler, means

for variably directing air through the casing to engage the heating surface, and means 45 for selectively delivering the heated air as desired, whereby a heat producing stream of exhaust gases is first brought into contact with the heating surface and subsequently with the muffling element.

2. In heaters, a suitable casing, a muffling element within the casing, a heat radiating surface forming the exterior of the muffler, means for variably directing air through the casing to engage the exterior of the heating surface, and means for selectively delivering the heated air as desired, whereby a heat producing stream of exhaust gases is brought into contact with the interior of the heating surface and the muffler.

3. In heaters, a car body, an engine exhaust, a muffler in the exhaust, a casing surrounding the muffler, an air inlet from inside the car body to the interior of the casing, an air outlet from the casing terminating within the car body, and means for variably controlling the air inlet and outlet as desired.

4. In automobile heaters, a car body, an engine exhaust, a muffler in the exhaust, a 70 heating chamber cooperating with the muffler, an air inlet from the inside of the car body to the heating chamber, an air outlet from said chamber terminating within the car body, and means for variably controlling 75 the air inlet and outlet as desired.

5. In heaters, a suitable casing, a heating surface within the casing, a muffling element within the heating surface, and means for variably directing cold air into contact with 80 said surface to extract heat from the exterior thereof simultaneously with the extraction of heat from its interior due to the muffling action.

In testimony whereof I affix my signature.
GEORGE H. EARLE.
